UNITED STATES PATENT OFFICE.

JAMES H. SKITT, OF PHILADELPHIA, PENNSYLVANIA, ASSIGNOR TO SMITH, DRUM & CO., OF PHILADELPHIA, PENNSYLVANIA, A CORPORATION OF PENNSYLVANIA.

CYLINDER CONSTRUCTION.

Application filed April 7, 1925. Serial No. 21,381.

This invention relates to rotary dyeing machines, and the principal object of the invention is to provide a cylinder so constructed as to be free from all sharp edges and 5 projections in the interior compartments which might injure the fabrics.

The invention further resides in the novel details of construction which render the cylinder easily manufactured and assembled 10 and very strong and durable.

As a further novel feature of advantage, the cylinder has a unitary structural feature making possible standardization of parts and the development from these parts of cylinders of varying lengths and containing different numbers of compartments for reception of the articles to be dyed.

In the attached drawings:

Figure 1 is a longitudinal section through 20 a cylinder made in accordance with my invention;

Fig. 2 is a section on the line 2—2, Fig. 1;

Fig. 3 is a section on the line 3—3, Fig. 2;

Fig. 4 is a section on the line 4—4, Fig. 2;

Fig. 5 is a section on the line 5—5, Fig. 2;

Fig. 6 is a view in perspective showing a fragmentary assembly;

Fig. 7 is a fragmentary section showing a detail of the construction;

Figs. 8, 9, 10, 11, 12, and 13, are detached perspectives illustrating elements of the construction, and

Fig. 14 is a fragmentary perspective of one of the longitudinal partitions.

With reference to the drawings, the cylinder comprises the usual central cylinder-supporting shaft 1 having near each end a collar 2 which, in each instance, constitutes an abutment for an end plate 3. The said end plates 3 are in each instance confined between the said collars 2 and a gear wheel 5 carried by the shaft 1, and the outer ends of the shaft are threaded for the reception of nuts 6, 6, which in assembly are screwed down against the hubs of the gears. Each of the face plates 3 has a peripheral lateral flange 7 to which are secured by means of rivets 9, arcuate plates 10 forming a cylinder wall 11.

The shaft 1 is provided, in the present instance, with three longitudinal radial grooves 12, 12 in which are seated the inner edges of three perforated partitioning plates 13 which divide the interior of the cylinder into three main longitudinal compartments. The end

edges of the partitioning plates 13 occupy grooves in radial bars 14 secured to the end plates 3 by means of studs 15 and 16, these studs also securing to the outer faces of the end plates three radial channel bars 17. 60 The studs 16, 16 also extend through the spokes or radial arms 18 of the gear wheel 5 and thereby secure the said gears to the ends of the cylinder and also confine between the end plates and the gears the inner ends 65 of the channels 17. The inner ends of the bars 14 closely fit the shaft 1 while the outer ends preferably bear neatly against the inner face of the cylinder wall 11.

Each of the partitioning plates 13 is, in the present instance, provided at its inner edge with two recesses 19 which are adapted to fit over and into radial grooves, 21, in a pair of hub elements 22, 22 on the shaft 1. Each of these hub elements 22 is also provided with a peripheral groove 23 adapted to receive the inner arcuate edge 24 of segmental partitioning plates 25, shown in perspective in Fig. 9. The side edges of these partitioning segments 25 occupy longitudinal grooves 26 in radial bars 27 and 28 respectively, the bars of each pair thereof being adapted to lie respectively on opposite sides of the longitudinal partitioning plates 13 with their inner ends occupying recesses 29—29 in the said hub elements 22, as clearly illustrated in Fig. 6. Each of the bars 27 is provided with dowels which extend through the apertures in the partitions 13 and enter holes formed for their reception in the bars 28, the dowels functioning to maintain the bars in position during the operation of the assembly. By means of the segmental partitions 25, each of the main longitudinal chambers of the cylinder formed by 85 the partition plates 13, 13 is divided, in the present instance, into three uniformly sized sub-compartments of generally segmental shape.

The outer edges of the segmental plates 25 100 occupy grooves 32 in curvilinear bars 33 mounted on the inside of the segmental cylinder plates 10 and these bars 33 are secured in place by means of studs 34 which project through the perforations in the said 105 cylinder plates 10 and through segmental bars 35 thereby securing both these latter bars and the bars 33 in place. The bars 35, as shown in Fig. 2, in each instance extend from one of the main partitions 13 to a point 110

short of an adjacent partition as clearly shown in Fig. 2, and are so shaped at the outside that when a guide plate 36 is placed on top and secured in place by means of the aforesaid studs 34, a channel 37 is provided at each side of the bar 35 between a shoulder on the latter and the nether side of the said plate 36. Each of the sub-compartments is provided with an opening, formed in the plates 10, through which the fabrics to be dyed may be placed in the cylinder compartments and these openings, designated in Fig. 2 by the reference numeral 38, are adapted to be closed by means of a door 39 whose side edges occupy the aforesaid grooves 37 and similar grooves 41 in a bar 42 held by rivets 9 to the flanges of the end plates 3. The bars 42 comprise the base 43, a spacer element 44 and the outer guide plate 45, the groove 41 being formed between the inner face of this guide plate 45 and the outer face of the base 43 by reason of the interposed spacer 44. As shown in Fig. 2, each of the plates 10 along one edge of the opening 38 is hooked over to engage the oppositely hooked edge 46 of the sliding door 39 and the end of each of the plates 36 is turned down as indicated at 47 to form a stop limiting the opening travel of the door 39 in its guide grooves.

Also as shown in Fig. 2, each of the partitions 13 projects beyond the cylinder wall 11 and has welded thereto the flanged edge 48 of one of the cylinder plates 10. This projecting joint is covered over and hidden by a bent over strip 49 which embraces the edges of the plate 10 and the partition 13 and also the upstanding flange of an angle bar 50 secured to the opposite side of the partition 13.

As shown in Fig. 5, the studs 34 are slotted at their inner ends for the reception of the plates 25 whereby the said studs are prevented from turning. It will also be noted that both the lateral partitions 25 and the longitudinal partitions 13 are perforated to allow free circulation of the dyeing medium through the articles confined in the chambers.

It will be noted that in the present instance there is shown no bolt or rivet extending into the chambers which hold the fabrics, the surfaces of these chambers being accordingly free from all inward projections which might present a sharp edge or part to injure the fabrics. Also, the parts may be utilized with various lengths of the cylinder plates 10 to provide any desired length of cylinder having any required number of chambers, the parts, with the exception of the cylinder plates and longitudinal partitions being standard for each diameter of cylinder.

I claim:

1. A cylinder for dyeing machines com-

prising a shaft, circular end plates secured to the shaft, a cylindrical shell secured to the end plates, longitudinal partitions extending radially from the shaft and dividing the interior of the cylinder into a plurality of compartments, segmental transverse partitions, and slotted members fitted to the said longitudinal partitions and to the shell and forming frames for reception of said transverse partitions. 75

2. A cylinder for dyeing machines comprising a shaft, circular end plates secured to the shaft, slotted members secured to the inner faces of said end plates, radial plates each having one longitudinal edge fitted into a longitudinal groove in the shaft and the end edges in the said slotted members, arcuate plates secured at their edges to the outer edges of said radial plates and to the end plates, segmental transverse partitioning plates, and slotted members fitted to the said longitudinal partitions and to the shell and forming frames for reception of said transverse partitions. 80

3. A cylinder for dyeing machines comprising a shaft having a plurality of longitudinal slots, circular end plates secured to the shaft in spaced relation; an annular element on the shaft intermediate the end plates, said element being slotted transversely in alignment with the said shaft slots and also circumferentially, slotted elements secured to the inner faces of the end plates and extending radially from the shaft, longitudinal partitioning plates seated in the said radial slotted elements and in the aligned slots of the shaft and annular element, slotted elements fitted to the said partitioning plates and extending radially from the shaft with their slots in alignment with the circumferential slot of said annular member, transverse partition plates mounted in the slots of the last named radial elements and in the circumferential slot of the annular member, and a cylindrical shell surrounding the partitions and secured to the end plates. 95

4. A cylinder for dyeing machines comprising circular and arcuate plates secured together to form a cylindrical shell, a plurality of slotted elements in the interior of said shell, studs extending from one side of said slotted elements whereby said elements are secured on the inside of the shell, and partitioning plates seated in the slotted members and dividing the interior of said shell into separate compartments. 100

5. A cylinder for dyeing machines comprising a cylindrical shell, slotted elements having studs extending from one side whereby said elements are secured on the inside of said shell, and partitioning plates seated in the slots in said elements. 110

6. A cylinder for dyeing machines comprising circular end plates and fixed and loose arcuate plates adapted to cooperatively

- form a cylindrical shell, longitudinal partition plates secured to said end plates and to said fixed arcuate plates for securing the elements of the shell together and dividing the shell into compartments, the loose arcuate plates being movable to permit access to the interior of said shell.
7. A cylinder for dyeing machines comprising a cylindrical shell, slotted elements extending around the inner circumference of said shell, transverse partitioning plates seated in said slotted elements, said shell having openings giving access to each compartment formed by said partitions, guides secured to the outside of the shell on both sides of each opening and in alignment with said slotted elements, common securing means for the guides and elements, and closure plates for the openings slidably supported in the guides. 15

JAMES H. SKITT.
